UNITED STATES PATENT OFFICE.

JOHN STEMBER, OF NEW YORK, N. Y.

DESIGN FOR A BODY FOR BELTS.

SPECIFICATION forming part of Design No. 33,440, dated October 23, 1900.

Application filed September 28, 1900. Serial No. 31,455. Term of patent 3½ years.

To all whom it may concern:

Be it known that I, JOHN STEMBER, a citizen of the United States, residing at New York, borough of Manhattan, and State of New York, have invented and produced a new and original Design for Bodies for Belts, of which the following is a specification, reference being had to the accompanying drawing, forming a part thereof.

As shown in the drawing, the leading or material feature of my design consists of a central leaf-like ornament A, at the sides of which radiate the foliated ornaments B. The

ornaments A and B are inclosed in a scalloped elliptic figure C.

What I claim is—

The design for a body for belts, substantially as shown and described.

In testimony that I claim the foregoing as my invention I have signed my name in presence of two subscribing witnesses.

JOHN STEMBER.
